EMMETT M. HOWARD, OF HIGH POINT, NORTH CAROLINA.

DESIGN FOR A PHONOGRAPHIC-RECORD-DISK CABINET.

55,613.

Specification for Design.

Patented July 6, 1920.

Application filed February 13, 1920. Serial No. 358,402. Term of patent 14 years.

To all whom it may concern:

Be it known that I, EMMETT M. HOWARD, a citizen of the United States, residing at High Point, in the county of Guilford, State of North Carolina, have invented a new, original, and ornamental Design for Phono-graphic-Record-Disk Cabinets, of which the following is a specification, reference being made to the accompanying drawing, forming part thereof.

The figure is a perspective view of a pho-

nographic disk record cabinet showing my new design, wherein 1 designates the cabinet having the front legs 2, the bottom front strip 3, the vertical parallel closely related partitions 4, and the record supports 5 having the front downwardly beveled outer ends 6.

I claim:—

The ornamental design for a phono-graphic record disk cabinet, as shown.

EMMETT M. HOWARD.
